UNITED STATES PATENT OFFICE

2,446,917

NURSING BOTTLE

Angelo I. Gaimari, Chicago, Ill.

Application December 28, 1946, Serial No. 719,063

5 Claims. (Cl. 215—11)

1

This invention relates to certain new and useful improvements in nursing bottles.

The invention contemplates the employment of a valve controlled stem arranged in a nursing bottle to facilitate the expulsion of the contents from the bottle with less effort when the bottle is held upright or tilted, with the result that substantially all of the contents of the bottle may be expelled during the nursing operation.

The invention also contemplates a nursing bottle of the description herein more fully set forth, which comprises relatively few parts, resulting in economical manufacture and assembly.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a vertical sectional detail view of the invention;

Fig. 2 is a vertical sectional detail view of the invention similar to that shown in Fig. 1 but showing the nursing bottle in a reversed tilted position; and

Fig. 3 is a fragmentary sectional detail view of the nursing bottle embodying my invention, illustrating a modified form of construction.

The several objects of my invention are best accomplished by the preferred form of construction now to be described.

Referring more particularly to Figs. 1 and 2, a bottle is indicated at 10. This bottle may be formed of any approved material and is preferably provided with a bowl shaped interior bottom 11 and a neck 12. Threaded into this neck 12 (or frictionally mounted therein, as may be desired) is a plug 13 having a reduced portion 14 to provide a flange 15, which bears against the adjacent portion of the neck 12. Threaded into this plug 13 is a stem 16 providing a reduced portion 17 on which is slidably mounted a valve sleeve 18, limited in its movement to a position to close an opening 19 by a collar 20 formed on the stem 16. The stem 16 is hollow in construction and may be formed of any suitable material. In the present instance, the stem, as shown in Fig. 1, extends well into the bowl-shaped bottom 11 so that when the bottle 10 is used in the position shown in Fig. 1, substantially all the contents of the bottle will be drawn therefrom.

The neck 12 provides a bead 21 and over this

2

bead 21 is adapted to be yieldably positioned a nipple 22 of any approved construction.

When the bottle is used in a substantially upright position, as shown in Fig. 1, or inclined from such position, the sleeve 18 will rest upon the collar 20 closing the opening 19 so that the contents of the bottle must be drawn through the stem 16.

However, when the bottle is in the position shown in Fig. 2, the sleeve 18 will move in a position against the plug 13 from closing position with respect to the opening 19, thereby allowing the contents of the bottle 10 to flow through the opening 19 into the nipple 22.

15 A nursing bottle constructed with a feeding stem similar to that indicated at 16 affords removal of substantially all the contents of the bottle regardless of which of the two positions the bottle is held in and greatly facilitates the extraction of the contents from the bottle during the nursing operation.

The parts are easily removable so that they may be cleaned and sterilized.

In Fig. 3, I have illustrated a slightly modified form of construction. In the illustration in Fig. 3, parts therein shown which are similar to those illustrated in Figs. 1 and 2, are indicated by similar reference numerals. The construction in Fig. 3 differs from that shown in Figs. 1 and 2 in that 30 the plug 13' provides above the flange 15 a curved extension 23 which disposes the nipple 22 at an inclination with respect to the longitudinal axis of the bottle 10. The advantages and the results of the construction shown in Fig. 3 are otherwise 35 the same as those resulting from the construction shown in Figs. 1 and 2.

While I have illustrated and described the preferred form of construction for carrying my invention into effect, this is capable of variation 40 and modifications without departing from the spirit of the invention. I, therefore, do not wish to be limited to the precise details of construction set forth, but desire to avail myself of such variations and modifications as come within the 45 scope of the appended claims.

Having thus described my invention, what I claim as new and desire to protect by Letters Patent is:

50 1. A nursing bottle providing a neck, a plug mounted in the neck, a hollow stem carried by the plug and extending into the bottle and having an opening formed therein adjacent to and below said plug, and a valve sleeve slidably mounted upon said stem for controlling passage through said opening.

2. A nursing bottle including a neck, a plug in said neck, a hollow stem extending from said plug into said bottle and terminating at a point adjacent to the bottom of said bottle and having a reduced portion with an opening formed therein adjacent to and below said plug, and a collar slidably mounted on said reduced portion for controlling passage through said opening.

3. A nursing bottle providing a neck, a plug mounted in the neck, a hollow stem carried by the plug and extending into the bottle and having an opening formed therein adjacent to and below said plug, and a valve sleeve slidably mounted upon said stem for controlling passage through said opening, said stem providing a collar for limiting movement of said sleeve to closing position with respect to said opening.

4. A nursing bottle including a neck, a plug in said neck, a hollow stem extending from said plug into the bottle and terminating at a point adjacent to and in spaced relation with respect to the bottom of said bottle and having a reduced portion with an opening formed therein, and a collar slidably mounted on said reduced portion for controlling passage through said opening, said stem providing a collar for limiting movement of

said sleeve to closing position with respect to said opening.

5. A nursing bottle including a neck and having an interior bowl-shaped bottom, a plug mounted in said neck, and a hollow stem carried by said plug and extending to a point within the bowl-shaped bottom of said bottle, said stem adjacent to and below said plug having an opening formed therein, and a valve member slidably mounted on said stem for controlling passage through said opening.

ANGELO I. GAIMARI.
